UNITED STATES PATENT OFFICE.

ROBERT B. HUGUNIN, MARY L. HUGUNIN, AND WILBER A. LANE, OF NORTH HAVEN, CONNECTICUT; SAID ROBERT B. HUGUNIN ASSIGNOR TO SAID MARY L. HUGUNIN AND WILBER A. LANE.

KNEADING-ROLLER AND RETIRING HANDLES THEREFOR.

SPECIFICATION forming part of Letters Patent No. 730,124, dated June 2, 1903.

Application filed August 20, 1902. Serial No. 120,302. (No model.)

To all whom it may concern:

Be it known that we, ROBERT B. HUGUNIN, MARY L. HUGUNIN, and WILBER A. LANE, at present residing at North Haven, in the county of New Haven and State of Connecticut, have invented certain new and useful Improvements in Kneading-Rollers and Retiring Handles therefor.

Our invention relates to improvements in kneading-rollers and retiring handles employed with the same, the objects of the improvements being, first, to enable the construction of several fluted rollers together at one time direct from the raw material; second, to enable the construction of several fluted rollers at one time, with flutes varying in depths and side angles, by means of which the material being worked is alternately compressed and stretched; third, the application to dough-working rollers of retrievable handles and handle-catches for securing the same and an expanding spring at the inner end of the handle-body to move the same outwardly within reach of the hand when the confining-catch is released. We attain these objects by means illustrated in accompanying drawings, in which—

Figure 1 is a plan view of a roller embodying our invention. Fig. 2 is a longitudinal view 30 of same, showing our handles retired. Fig. 3 is an end view of roller having our improvements. Fig. 4 is a cross-section of the same and of material from which we preferably form the roller. Fig. 5 is a cross-sectional view 35 of half of a roller, the other half being shown in dotted lines; Fig. 6, sectional plan of our retiring handle; Figs. 7 and 8, views showing application of handle-fastening catches to ends of roller; Fig. 9, view of a disconnected 40 handle-catch and screw; Figs. 10 and 11, modification in construction of our roller; Figs. 12 and 13, modifications in construction of retiring handles for rollers. Fig. 14 is a view of retiring handle, modification shown 45 in Fig. 13, the spring being omitted; Fig. 15, washer and screw for securing handle, modification shown in Fig. 13; Figs. 16 and 17, cross-sections of fluted rollers, showing modification of features of our fluted roller.

Similar letters refer to similar parts in all 50 the figures.

A is a cross-section of material from which we form our fluted roller, round, fluted, and solid, several lengths at a time, by single cuttings from each of the planes *b c d e*, inclosing the material, as shown in Fig. 4, and a cross-section of material from which our roller is formed in halves, several lengths at a time, by a single cutting from each of the planes *f g*, as shown in Fig. 5, subsequently cut to lengths 55 of roller and secured together.

A' is a cross-section of material from which a modified form of roller possessing features of our invention is cut round and fluted, several lengths at a time, by two cuttings from 65 planes *b' d'*, as shown in Fig. 16, also a cross-section of a modified roller possessing features of our invention, cut both round and fluted, several lengths of rollers at a time, by four cuttings from planes *b' c' d' e'*, as shown 70 in Fig. 17.

B is the body of our fluted roller embraced within planes *a a a a*, from which as a base our improved flutes are constructed. (See Fig. 3.) For a modified construction of same 75 see Fig. 10.

B' is a modification of roller-body embraced within planes *a' a' a' a'* and flutes projected from same, as shown in Fig. 16. Also a modified form in construction of our flutes is shown 80 in Fig. 17.

A modified construction of our roller in sections is shown in Fig. 10, the body of the roller being constructed separately from the flutes and the sections united in construction, 85 as shown in Fig. 11. When the sections are united, this modified construction of roller embraces the features of our invention shown in Fig. 3.

C C are flutes preferably constructed in 90 form to give alternate varying depths and side angles, as shown in Fig. 3, and thereby greater smoothness in working, and by means of which the material is alternately compressed and stretched as under pressure in 95 bread-kneading. The flutes are shown projected from planes *a a a a* at right angles to planes *h h*, passing quarterly through the

roller-center, as shown in Fig. 3, the nearest to a right-angle side of the flute being, preferably, the corner side of the same, as shown in Fig. 3.

5 The construction of the retiring handle is shown in Fig. 6, in which E is the handle-body, F the handle-pin secured to same, having movable handle G secured loosely to pin F by means of knob M and the spring J 10 acting from the inner end of the handle-body, as shown in Fig. 2.

Figs. 12 and 13 are modifications of retiring handles, showing handle-body E', pin F', handle G', spring J', and washer H', and 15 screw I' for securing the handle in moving position on pin F'. The washer and screw are shown in Fig. 15 in detail.

Fig. 14 shows an end of roller B, roller-opening D, and body of retiring handle E', 20 with the spring (shown in Fig. 13) omitted.

Fig. 9 illustrates the securing-catch K and screw I detached from end of roller; D, opening at ends of roller corresponding with and for the admission of retiring-handle body E.

25 F is the handle-securing pin, connected with body E; G, movable handle secured loosely to pin F by knob M, as shown in Fig. 6, or by washer H' and screw I', (shown in modification, Figs. 12 and 13;) J, compressible

30 coiled spring employed at inner end of handle-body E in retiring-handle opening D; K, catches for securing retiring handles; L, holes in handle-bodies E for tongues of catches K, by means of which the handles are secured

35 when drawn out, as shown in Figs. 1 and 7, and when retired, as shown in Figs. 2 and 8. On releasing the catches the spring J forces the handle outwardly within reach of the hand for adjusting and securing in working

40 position. By retiring the handles when not in use the space occupied by the roller is lessened by the lengths of the retiring handles, adding to compactness and convenience of roller.

45 The retiring handles are equally adapted to the plain rolling-pin and to which we apply them. The fluted roller is also adapted to the plain rolling-pin handles and to which we apply them when desired. Our kneading-

50 roller is also adapted for employment with

power and can be made of any required diameter and number of flutes projected and cut, both round and fluted, several lengths at a time from planes inclosing the material from which formed, requiring one cutting 55 from each plane, including flutes located on same.

We are aware that radiating fluted rollers, the product of two operations, turning and fluting, with considerable difficulty in graduating have been made, and we do not broadly claim such; but

What we do claim, and desire to secure by Letters Patent, is—

1. The kneading-roller herein described, 65 constructed with uniformly-shaped flutes, one side of the flute being nearly at right angles with, and the other at a less angle with the base of the same, in application alternately reversed, providing thereby, alternate and 70 uniformly-varying depths, with uniform side angles between the said flutes, substantially as shown, and for the purposes specified.

2. The kneading-roller herein described, 75 constructed in sections, one section a square, the other of flutes constructively united in pairs, and applied to sides of said square, substantially as shown, and for purposes specified.

3. The combination with a roller of the retiring handles herein described, constructed 80 arranged and applied substantially as shown and for the purposes specified.

4. The combination with a kneading-roller 85 of the retiring handles herein described, each constructed and working independently of the other, each having a handle-body, and handle-pin to which the handle is movably attached, a fastening-catch adapted both to secure the body of handle within roller, and 90 when drawn out for use and a compressible coiled spring all applied and working substantially as shown, and for purposes specified.
